CARTRIDGE GUIDE DEVICE FOR
REPEATING FIREARMS

Ellis Warren Chapin, Chicopee Falls, and Louis Elkas, West Springfield, Mass., assignors to Savage Arms Corporation, Utica, N. Y., a corporation of Delaware

Application December 13, 1949, Serial No. 132,762

1 Claim. (Cl. 42—18)

1

This invention relates to a device for guiding cartridges from a box type magazine to the firing chamber of a bolt action repeating rifle.

An object of the invention is to provide a guide device to facilitate the use of a front locking type breech bolt in a small caliber rifle.

Another object is to provide a guide structure permanently fixed between the magazine clip and the firing chamber to direct the nose of a cartridge from the magazine upwardly into the firing chamber as the cartridge is fed forwardly by the bolt.

A further object is to provide a guide device in the receiver to insure a predetermined relative position of the guide to the magazine.

These and other objects will be readily understood from the following description and accompanying drawings, in which:

Fig. 1 is a side elevation of the device assembled on a rifle with its magazine clip mounted in position and its receiver shown in section with the action open;

Fig. 2 is a similar view with the bolt moved forwardly to show a cartridge being guided by the device;

Figs. 3 and 4 are partial views showing the relation of parts with the bolt shifted forwardly and in unlocked and locked position respectively; and

Fig. 5 is a view on line 5—5 of Fig. 1.

Generally, small caliber bolt action repeating rifles are provided with a reciprocable bolt of a rear locking type. It is characteristic of this type of bolt that the rear portion thereof only is rotated in the receiver to lock the action. The fore portion, which in firing position overlies the magazine clip, remains stationary. Consequently, as is well known to those skilled in the art, the under surface of the fore portion of the bolt is generally slotted longitudinally to receive therein the top edges of a magazine in the forward shifting of the bolt to firing position. In this type of construction a magazine is thus in a relatively high position in the receiver assembly so that a top cartridge may be substantially in horizontal alignment with the firing chamber of the rifle. A cartridge may therefore be fed from the clip and more or less directly inserted into the firing chamber.

In providing a front locking type of bolt in a small caliber rifle the relative position of the magazine in the receiver assembly must be changed. Inasmuch as the bolt is locked by rotation of its fore portion it can not be provided with slots for the top edges of the clip. The

2

magazine must lie entirely underneath the path of the bolt. The lowered position of a top cartridge in this event is out of a generally horizontal alignment with the firing chamber. The top cartridge fed from the lower position of the clip will not be directed more or less straight forwardly for insertion in the firing chamber and will jam the action of the rifle by lodging its nose on the breech face of the barrel rather than in the firing chamber.

In the drawings a receiver assembly showing a front locking type bolt 1 is illustrated by Fig. 1 with the action open. An offset locking lug 2 at the front of the bolt is rotatable with the bolt 5 through 90° to a locked firing position as in Fig. 4. The extractor 3 of the bolt is shown at the front thereof and it will be noted that the lower corner 15 of the extractor recess 4 is provided with a beveled nick as at 5 for a purpose to be later described.

A magazine 6 is held in the usual elongated opening in the lower wall of the receiver and in position below the path of the slidable bolt by complementary spring clip arms as 7 and 8 at 20 the front and rear respectively of the magazine opening. Arms 7 and 8 are secured to the underside of the receiver, the rear arm 8 having a finger piece at its lower end for releasing the magazine from the assembly. Arm 8 is provided 25 with ears 8' in rear edge keeper slots to hold the magazine latched in position.

A spring pressed follower 9 constantly urges cartridges upwardly toward the top of the magazine for the successive feeding thereof into the 30 firing chamber of the rifle. The firing chamber is spaced forwardly and upwardly in the receiver from the fore end of the magazine opening and is chambered for rotation of the lug 2 to lock the action as will be readily understood. A top 35 cartridge is held in the magazine against the action of the follower 9 by inwardly flanged lips 10 at the upper rear portion of the magazine side walls. As the bolt 1 is shifted forwardly to close the breech of the rifle, the top cartridge is carried 40 forwardly by the bolt engaging the top of its rim as far as two complementary side wall cutouts 11. Here the action of the follower 9 causes the cartridge to spring upwardly out of the magazine into a cartridge rim recess 12 in 45 the face of the bolt where the rim of the cartridge slides under the hook of extractor 3. Before the advancing cartridge reaches the cutouts 11, however, and while its rim remains held by the flanged lips 10 as shown by Fig. 2, the pressure 50 of the bolt on the uppermost portion of the rim

tends to cause the cartridge to nose downwardly, the rim edge on the surface of the next subjacent cartridge serving continually as a pivot point. The spring pressure of the normally upwardly inclined follower is not alone sufficient to resist this downward pivoting action. To prevent such downward nosing of a cartridge and to guide it upwardly for accurate placement of the nose in the firing chamber, the guide device of this invention is provided in the receiver between the front edge of a magazine in the assembly and the firing chamber opening. The guiding operation of the device is shown by Fig. 2. When the cartridge rim is released from cutouts 11 and positioned in recess 12 of the bolt face, the nose of the cartridge has been angularly placed in the chamber opening. The bolt can then be closed and locked.

Normal position of the guide device in the breech assembly is best seen by Figs. 1 and 2. As there shown, it is mounted on the horizontal leg of the front spring arm 7 which as shown is bolted to the under side of the receiver. A narrow slot 15 extending forwardly from the magazine opening is provided for the upward extension of two eared portions 13 bent upwardly from the leg to form spaced supports for the device (Fig. 5). Between the ears 13 is mounted a pin 14 and pivotally mounted on the pin are two legs of an inverted U-shaped rocker member 16.

The upper surface of the member serves to provide a slidable bearing support for a cartridge nose in bridging the gap between the top of the magazine and the chamber opening. The bearing surface of the rocker is centrally depressed as at 17 longitudinally of the cartridge path in the fashion of a chute or ramp as by deforming the metal thereof.

The lower edges of the legs are rounded at the front and offset at their rear portions, the latter providing stops against counterclockwise rotation of the rocker from the position of Figs. 1 and 2 as seen in the drawings. The rounded portions permit clockwise rotation (Figs. 3 and 4). A stiff torsion spring 18 is spirally wound on pin 14 with one end keyed under the cross piece of the slide and the other on the horizontal leg of arm 7. Spring 18 thus yieldably urges the rocker to the upstanding normal operative position of Figs. 1 and 2.

When a top cartridge is fed out of the magazine into the firing chamber by the forwardly shifted bolt, the nose of the cartridge is initially inclined upwardly by follower 9 (Fig. 1). As it is urged toward the firing chamber bearing surface 17 of the rocker receives the nose to cradle it in an upwardly inclined direction thus preventing the tendency to nose downwardly. Accurate placement in the firing chamber opening is thus assured.

It will be noted that the front or upper edge of surface 17 adjacent the firing chamber is symmetrically beveled off toward the chamber as at 19 (Fig. 1) so as not to impede further movement of the cartridge into the chamber. When a cartridge is carried with its rim in recess 12 of the bolt face and its nose in direct alignment with the firing chamber, the cartridge guide has performed its intended function. This will be readily seen from the dotted line position of the cartridge as in Fig. 2. As the bolt is closed and locked (Figs. 3 and 4) the rocker is pivoted

longitudinally of the receiver on pin 14 and forwardly to lie below the opening of the firing chamber as shown.

In Fig. 4 the bolt has been rotated 90° to lie with the top lug locked in the receiver as will be readily understood. It is to be noted that clearance is provided for the turning of the extractor arm and hook with the bolt by a chamfered lip section of the firing chamber opening as at 20. When the bolt is locked in the position of Fig. 4, it will be appreciated that the extractor arm recess 4 overlies the rear edge of the bearing surface of the rocker and encloses the latter between the side edges of the recess. As seen by Fig. 4, the rocker 16 is pivotally urged against the bolt body by its spring 18. In order to prevent the rear edge of the rocker from catching in the recess 4 and impeding rotation of the bolt in unlocking the same, the far edge of the rocker bearing face is beveled to bear against the beveled nick 5 of the slot. This beveling of the rocker edge is shown clearly by Fig. 5 as at 21. As the bolt is rotated out of the locked position of Fig. 4, the beveled nick 5 and edge portion at 24 bear against each other and cam the rocker downwardly to the position of Fig. 3. It is thus cleared from the rotating edges of slot 4.

What is claimed is:

In a bolt action repeating rifle, a receiver having an elongated opening in the lower wall thereof to receive a box type magazine in said opening, a firing chamber spaced forwardly and upwardly from the front edge of said opening, a bolt of the front locking type reciprocable in the receiver and rotatable over said opening in its forward position to lock the bolt in the receiver, said receiver at the front edge of said opening having a slot extending forwardly from the opening below said firing chamber, a magazine spring clip anchored to said receiver in front of said slot and extending rearwardly to cover the slot and downwardly at the front edge of said opening, a cartridge guide mounted on said clip projecting upwardly through said slot with its upper portion adjacent said firing chamber, said guide comprising a rocker member, a pivotal connection between said spring clip and rocker member and a rocker spring urging said member to a rearward upright position, said rocker having an inclined upper surface for engaging the nose of a cartridge urged forwardly by said bolt and directing said nose into the opening of the firing chamber, said rocker being forwardly pivotable by said bolt to a forward position under the opening of said firing chamber, said bolt having an extractor slot and an extractor arm at the forward side edge thereof rotatable against said rocker with said extractor slot having a beveled corner edge for contact with said rocker during rotation of said bolt into and out of locked position.
